FIG. 3.

UNITED STATES PATENT OFFICE.

FRANCIS O. HELTZEL, OF WARREN, OHIO.

CAR UNLOADER.

Application filed October 9, 1920. Serial No. 415,865.

To all whom it may concern:

Be it known that I, FRANCIS O. HELTZEL, a citizen of the United States, residing at Warren, in the county of Trumbull and State of Ohio, have invented certain new and useful Improvements in Car Unloaders, of which the following is a specification, reference being had therein to the accompanying drawing.

10 The present invention relates to a car unloader, and aims to provide a novel and improved device of that character including a skip mounted for rocking movement and arranged to be supported from the side 15 wall of a car, whereby coal, sand or other material can be readily unloaded, by shoveling same into the skip or receptacle and then tilting such skip to dump the material into a wagon or other receiver underneath, 20 thereby facilitating the unloading operation without interruption.

Another object of the invention is the provision of such a device comprising a skip or receptacle mounted for rocking movement in a novel manner upon and between brackets supported from the car wall, and providing for the advantageous rocking or tilting movement of the skip, as well as holding the skip and brackets in place.

30 It is also an object of the invention to provide a car unloader of the kind indicated, which is comparatively simple and inexpensive in construction, as well as being thoroughly efficient and practical in use.

35 With the foregoing and other objects in view, which will be apparent as the description proceeds, the invention resides in the construction and arrangement of parts hereinafter described and claimed, it being understood that changes can be made within 40 the scope of what is claimed without departing from the spirit of the invention.

The invention is illustrated in the accompanying drawings, wherein:—

45 Figure 1 is a side elevation of the unloader showing the skip in filling or receiving position in full lines and in dumping position in dotted lines.

Fig. 2 is a plan view of the device.

50 Fig. 3 is an outer elevation thereof.

Fig. 4 is an enlarged detailed view showing one of the rockers in side elevation.

Fig. 5 is an edge view of the parts shown in Fig. 4.

55 The skip or receptacle 7 is constructed

of suitable sheet metal and has a bottom 8 curved or concaved forwardly and rearwardly, and the vertical sides 9, the forward portion of the bottom 8 being inclined, and providing a discharge spout for the 60 skip, while the inner or rear portion of the skip is open, as at 11, for convenience in shoveling or otherwise removing the contents of the car and placing same within the skip. The upper edge portions of the 65 sides 9 are bent outwardly at an angle, and thence downwardly, as at 12, to stiffen and reinforce such edges, to withstand wear and tear. Angle irons 13 are secured to the skip along and underneath the forward and 70 rear ends of the bottom 8, to stiffen and reinforce them, whereby the skip is substantial and strong in construction.

In order to support the skip at the exterior of the car, a pair of brackets 14 are 75 provided. These brackets are constructed of angle iron, as shown, and each of them has the upper inclined rail 15, and an inclined brace 16 underneath united at its forward upper end with the outer forward 80 end of the rail 15 and said rail and brace are connected by the rear and intermediate stays 17 and 18, respectively. The rear terminal of the rail 15 projects beyond the stay 17, and lower end of the brace 16, and is bent into a hook 19 to engage behind the upper edge of the car wall W , as seen in Fig. 1, with the lower ends of the brace 16 and stay 17 bearing against the wall on the outside, whereby the bracket is supported in 90 a simple and convenient manner. Such brackets 14 can be quickly applied to the car, and shifted or moved to different positions thereof with ease and dispatch.

The skip is supported from and located between the brackets 14, and is mounted for rocking motion, and, for this purpose, rockers are secured to the sides 9 of the skip, to roll or rock on the brackets. These rockers comprise plates 20 bearing flatly 100 against the sides of the skip near the centers of said sides, and the plates have ears 21 secured by rivets or otherwise to the skip sides. Each rocker plate 20 has an offset lower gear segment or toothed rocker portion 22. Each rail 15 has an inner upstanding flange, and a lower outwardly extending flange, and the corresponding segment 22 bears on the upstanding flange, which flange has the rack teeth 23 with 110

which the teeth of the segment 22 mesh, thereby preventing the rocker from slipping longitudinally on the rail and maintaining the skip in proper operative position for rocking movement. Each segment 22 is shrouded, being provided with the shrouds or flanges 24 at the opposite sides projecting beyond the segments 22 and overlapping the opposite sides of the toothed flange of the rail 15, as seen in Figs. 4 and 5, whereby to hold the rockers in place on the rails 15, and to also maintain the brackets 14 and skip in proper relative transverse position. Thus, the rockers being mounted on the brackets, will hold the brackets in place adjacent to the skip.

In using the unloader, the brackets 14 are engaged with the car wall at the proper position, by placing the hooks 19 over the upper edge of the wall, and the brackets then swing downwardly against the exterior of the wall by gravity. Then, the skip is placed between the brackets and the rockers seated on the brackets, so that the inner or rear end portion of the skip will seat on the upper edge of the car wall as seen in Fig. 1. The rockers are positioned slightly outwardly or forwardly from the center of gravity of the skip, whereby the inner or rear portion of the skip is heavier than the outer or forward portion, so that the skip will rock backwardly by gravity and assume its filling or receiving position, as seen in full lines in Fig. 1. It is then an easy matter to shovel the material from within the car into the skip, the top and inner end of which are open, and during the filling of the skip, a wagon or other receiver can be brought to position under the skip, without interruption.

When the skip is filled, it is an easy matter to rock the same forwardly or outwardly to dumping position, as seen in Fig. 1, whereby the material in the skip gravitates from the outer forward spout portion of the skip into the wagon or receiver underneath. The skip, when emptied, will swing back to receiving position, ready to be refilled.

The two brackets 14 are independent and individual, being disconnected from one another, so that they can be placed within the skip when not using same, but it will be noted that when the rockers are engaged on the brackets, the brackets and skip are held and maintained in assembled relation.

This also enables the same brackets to be used with skips of different widths.

Having thus described the invention, what is claimed as new is:—

1. A car unloader comprising a pair of brackets each having an inclined rail and means at the lower end of the rail for engaging over the upper edge of a car wall, a skip located between said brackets, and rockers secured to the sides of the skip and seated on said inclined rails for rolling motion, said brackets and rockers having teeth meshing with one another, and said rockers being located outwardly beyond the center of gravity of the skip so that the inner portion of the skip overbalances the outer portion, the bottom of the skip being concaved to seat on the upper edge of said car wall.

2. A car unloader comprising a pair of brackets each having an inclined rail and means at the lower end of the rail for engaging over the upper edge of a car wall, a skip located between said brackets, and rockers secured to the sides of the skip and seated on said inclined rails for rolling motion, said brackets and rockers having teeth meshing with one another, and said rockers being located outwardly beyond the center of gravity of the skip, so that the inner portion of the skip overbalances the outer portion, the inner portion of the skip being seatable on the upper edge of said car wall.

3. A car unloader comprising a pair of brackets each having an inclined rail and means at the lower end of the rail for engaging over the upper edge of a car wall, each rail having an upstanding flange with notches in the edge thereof forming teeth, a skip located between said brackets, and rockers secured to the sides of the skip and seated on the edges of said flanges for rolling motion thereon, the rockers having teeth meshing with the aforesaid teeth, said rockers being located outwardly beyond the center of gravity of the skip so that the inner portion of the skip overbalances the outer portion, and said rockers being shrouded to overlap the opposite sides of said flanges to prevent relative transverse displacement of the brackets and skip.

In testimony whereof I hereunto affix my signature.

FRANCIS O. HELTZEL.
